FIG. 8

FIG. 1 is a side elevational view of a fishing lure showing my new design, the side not shown being identical to the side shown;

FIG. 2 is a top plan view of the lure shown in FIG. 1, showing in dotted lines for illustrative purposes only live bait which may be attached to my lure, the bottom of the lure being identical to the top view with the deletion of eye for attaching a fishing line;

FIG. 3 is a front elevational view of the lure shown in FIG. 1;

FIG. 4 is a rear elevational view of the lure shown in FIG. 1;

FIG. 5 is a side elevational view showing a slightly modified form of my new design;

FIG. 6 is a top plan view of the lure shown in FIG. 5, the bottom of the lure being identical to the top view with the deletion of the eye for attaching a fishing line;

FIG. 7 is a front elevational view of the lure shown in FIG. 5; and

FIG. 8 is a rear elevational view of the lure shown in FIG. 5.

I claim:

The ornamental design for a fishing lure, as shown and described.
